(57) **CLAIM**

We claim the ornamental design for an air mover grill set and control panel combination, as shown and described.

DESCRIPTION

FIG. 1 is a front perspective view of an air mover grill set and control panel combination showing the new design;

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines in the drawings showing environmental subject matter are for illustrative purposes only and form no part of the claimed design.
